UNITED STATES PATENT OFFICE.

HIRAM C. BURK, OF CLEVELAND, OHIO.

DESIGN FOR A CORNER-PIECE FOR STAIRCASES.

SPECIFICATION forming part of Design No. 33,298, dated October 2, 1900.

Application filed July 27, 1900. Serial No. 25,057. Term of patent 7 years.

To all whom it may concern:

Be it known that I, HIRAM C. BURK, residing at Cleveland, in the county of Cuyahoga, State of Ohio, have invented and produced a new and original Design for a Corner-Piece for Staircases, of which the following is a specification, reference being had to the accompanying drawings, forming part thereof.

Figure 1 is a face view thereof, showing my new design. Fig. 2 is a rear view. Fig. 3 is a side view. Fig. 4 is a transverse section on line X X, Fig. 1.

As shown in the drawings, the leading or material feature of my design consists of a truncated pyramid A, the base of which is intersected by a segment of a great circle B,

thus leaving the base-lines of the pyramid-
arcs of great circles at C. The corners of the
base are rounded at D, and the apex is cut
off squarely at E.

Having described my invention, what I
claim as new, and desire to secure by Letters
Patent, is—

The design for a corner-piece for staircases,
substantially as shown and described.

In testimony whereof I have signed my
name to this specification in the presence of
two subscribing witnesses.

HIRAM C. BURK.

Witnesses:

WM. M. MONROE,
R. M. BROWNE.
